HEADREST FOR SHAMPOO PURPOSES

Maurice Pottern, Springfield, Mass.

Application July 1, 1932, Serial No. 620,383

5 Claims. (Cl. 4—159)

This invention relates to improvements in head rests for shampoo purposes for supporting the head of a person while having the hair washed, or shampooed. An object of the invention is to support the head that it will prevent water and soap from entering the eyes, or in other words, to form a water-tight joint, between the support and the part of the head above and around the eyes.

10. This invention, broadly considered, comprises a framework adapted to be supported on the edge of a wash stand and over the bowl portion and with means for suitably adjusting the same, relative to the bowl. A part, comprising a U-shaped member, is attached to the supporting framework by means of a hinge connection and removably located on the U-shaped member are rubber tubes on which the head of a person rests, when in use. Means are provided for pivotally 15 and vertically adjusting the U-shaped member.

20. Referring to the drawing:—

Fig. 1 is an end elevational view, considered on the line 1—1 of Fig. 2, showing the head rest in use and indicating, in outline, the head of the 25 person resting on the support.

Fig. 2 is an end elevational view looking from the left of Fig. 1, clearly showing the adjustable features, both vertical and horizontal, and a portion of the wash bowl on which the support rests, 30 and

Fig. 3 is a top plan view showing the support, before the head of the user is placed on the support and illustrating side extensions of the U-shaped member.

35. Referring to the drawing in detail:

1 designates a top portion of a wash stand having the usual recessed edge 2. Located on the recessed edge portion are the two T-shaped members 3, preferably formed of suitable material 40 that is not acted on by the action of soap and water, as aluminum, or nickel-plated material. 4 designates rubber tips, that are placed on the ends of the members 3, to prevent marring the wash stand. Suitably secured to the portions 5 are the rod members 6 which may comprise a tubular construction, each having the slots 7. The inner ends of these members are slipped 45 into the ends of the intermediate tubular member 8. Secured to the tubular member 8 are the pins 9, which enter the slots 7. Mounted on the tubular member 8 is the sleeve 10 which is secured in place with the set screw 11. Passing vertically through the sleeve 10 is the depending rod 12, which is adjustably retained in place with the 55 thumb screw 12'. Attached to the upper end of

the rod 12 is the pivoted bracket member 13, by means of the pivot pin 14. Located and secured in the bracket member 13 is a U-shaped rod 16, having the lateral ends 16', shown in dotted lines in Fig. 2. This rod is secured to the head portion 13, by any suitable means, as brazing or soldering.

Slipped onto the opposite ends of the U-shaped rod 16 are the tubular members 17 and 18, that are composed of soft rubber. The ends of these rubber tubes extend at right angles to the plane of the main portion of the U-shaped support, which, as shown, is parallel with the rods 6 and 8, as shown in the plan view in Fig. 3, and also in Fig. 1, as indicated at 19 and 20, whereby the 60 support will engage the side of the head of the wearer, or user, as shown in Fig. 1 in use.

65. The device, in use, is illustrated in Figs. 1 and 2, which shows the head, indicated at 20', resting in a horizontal position on the support and one 70 of the side pieces, as 20, engaging the side of the head; the forward part of the head being supported, shown in Fig. 2, at 21.

75. It will be seen, from this description, that I have provided a head rest that is inexpensive to 80 construct; one that can be quickly adjusted for different sizes of wash bowls and also vertically adjusted for the user, by means of the thumb screw 12' and forwards and rearward by the pivot pin 14. In Fig. 1, is shown the water and 85 soap dripping from the top of the head, indicated at 22, as the soft rubber tubes 17 and 18 provide a water-tight protection.

What I claim is:

1. In a device for the purpose described, T- 90 shaped supporting portions for engaging the recessed edge of a wash stand, rod members secured to the T-shaped supporting portions, a tubular member into which the ends of the rod members are inserted, a sleeve fixedly secured to the tubular member, a head-supporting part that is substantially U-shaped, and means for attaching the U-shaped head-supporting part to the sleeve. 95

2. A device for the purpose described, supporting portions for engaging the recessed edge of a wash stand, rod members secured to the supporting portions, a tubular member into which the ends of the rod members are slidably inserted, a sleeve fixedly secured to the tubular member, a head-supporting part that is substantially U- 100 shaped, means for attaching the U-shaped head-supporting part to the sleeve, the U-shaped member having tubular rubber members located thereon, and said U-shaped member having an offset portion at its upper ends at right angles 105

110

thereto for engaging the side of the head of the user, as shown and described.

3. A support for barbers' use for shampoo purposes comprising a U-shaped member, removable rubber cushion devices thereon, the opposite ends of the U-shaped member being offset at an angle thereto for engaging the side of the head of the user, means for supporting the U-shaped member over the bowl of the wash stand comprising a pair of T-shaped members, rods connected thereto, an adjustable sleeve part connected to the rods, a part pivotally connected to the U-shaped member and to the said sleeve part, whereby the U-shaped member may be adjusted, both vertically and horizontally, as described.

4. A device for shampoo purposes comprising, in combination, adjustable T-shaped members for engaging a wash stand, a vertically adjustable member connected to the said adjustable mem-

bers, a U-shaped member, means for pivotally connecting the U-shaped member to the vertically adjustable member, rubber tubular members on the U-shaped member for providing a water-tight cushion support for the user.

5. In a shampoo device two oppositely disposed T-shaped members for engaging the upper surface of a wash bowl, a slotted rod permanently secured to each of the T-shaped members, a tubular member into which the said slotted rods enter, a pin in the ends of the tubular member and located in the slots of each rod, a sleeve fixedly secured to the tubular member, a post adjustably secured to the sleeve, a member pivotally connected to the post, a U-shaped member secured to the pivotally connected member, and rubber coverings on the U-shaped member.
